PC(57) **CLAIM**

The ornamental design for a casing for blower, as shown and described.

DESCRIPTION

FIG. 1. is a first perspective view of the front, left, and top sides of a casing for blower showing our new design;

FIG. 2. is a second perspective view of the front, right, and bottom sides thereof;

FIG. 3. is a front view thereof; a rear view being a mirror image thereof

FIG. 4. is a left side view thereof;

FIG. 5. is a right side view thereof;

FIG. 6. is a top plan view thereof;

FIG. 7. is a bottom plan view thereof;

FIG. 8. is a cross-sectional view at 8-8; and,

FIG. 9. is a cross-sectional view at 9-9.

The broken lines shown represent portions of the casing for blower and form no part of the claimed design.

The dash-dot lines represent the boundary between the claimed design and unclaimed design and form no part of the claimed design.
